UNITED STATES PATENT OFFICE.

VIRGIL W. BLANCHARD, OF NEW YORK, N. Y., ASSIGNOR TO JOSEPH A. DAVIS, OF SAME PLACE.

SLIDEWAY FOR CROSS-HEADS.

SPECIFICATION forming part of Letters Patent No. 413,904, dated October 29, 1889.

Application filed April 9, 1889. Serial No. 306,532. (No model.)

To all whom it may concern:

Be it known that I, VIRGIL W. BLANCHARD, of New York, in the county of New York and State of New York, have invented certain new and useful Improvements in Slideways for the Cross-Heads of Steam-Engines; and I do hereby declare that the following is a full, clear, and exact description thereof, reference being had to the accompanying drawings, and to the letters of reference marked thereon, which form part of this specification, in which—

Figure 1 is a cross-section through a modified construction of a slideway, indicating in dotted lines a cross-head and the end of a piston-rod applied thereto. Fig. 2 is a side view of the same. Fig. 3 is cross-section through the slideways and cross-head of steam-engine. Fig. 4 is a reduced plan view thereof.

The object of this invention is to adjust the cross-heads of a steam-cylinder piston-rod so that the piston will not wear the cylinder; and it consists in means, which will be hereinafter explained, for effecting the object in view. Before describing my present invention I will state that I have fully set forth in another application for an improved steam-engine, filed April 9, 1889, Serial No. 306,536, means for sustaining a piston outside of the cylinder-heads, and therefore my present invention relates simply to the means for adjusting the cross-heads to which the piston-rod is attached.

Referring by letter to the drawings, Figs. 2 and 3, A designates the support of the slideways, and having angular side cheeks A' A', on which rest the angular slideways B B. These slideways are slotted transversely at the bottom, as at b, and in these slots lie angular gibs C C, the outer ends of which pass through openings in the cheeks A', and are screw-threaded and provided with adjusting and locking nuts C' C', as shown. By this means the slideways can be vertically adjusted. The slideways B are vertically slotted, as at D D, in their outer faces and at points intermediate between slots b, said slots being T-shaped in cross-section, and in these slots engage the enlarged heads of bolts E, the threaded ends of which pass through openings in the sides of cheeks A' and are pro-

vided with adjusting and locking nuts, as shown.

F F designate bolts passing through slotted openings in the bottoms of slideways B B.

G G designate plates secured on the top of slideways B by bolts g, and which prevent vertical movement of the cross-head H on said ways. The slideways can be vertically adjusted independently of each other by gibs C C, and when so adjusted securely locked in position by the bolts E and F, as described.

In Figs. 1 and 2, H designates slideways which are rectangular pieces of iron adapted to receive a cross-head. These slideways are slotted or recessed at b' and g, and they receive screw-bolts which have a head on one end and a nut on the other, and which are tapped through one of the cheeks I' of the support I.

The slideways H are supported upon a gib which is longitudinally adjustable and which is preferably adjusted by means of a nut m. The upper portion of this gib or wedge is horizontal to the slideways H H, and the gib is locked by means of screw-bolts L L.

It will be observed from what I have above described that the slideways are adjustable horizontally and vertically, the object of which is to center the piston-rod; also, that by my invention I am able to adjust a piston-rod both vertically and horizontally, and thereby keep the center of the piston in exact coincidence with the axis of the cylinder of the engine.

Having described my invention, what I claim as new, and desire to secure by Letters Patent, is—

1. Slideways for a cross-head of an engine, which are adjustable vertically and horizontally, substantially as described.

2. The combination of the frame, the vertically and horizontally adjustable slideways, and the screw-bolts, jam-nuts, and endwise-adjustable gibs, substantially as described.

3. The combination of vertically and horizontally adjustable slideways, the supporting-frame, screw-bolts tapped through the cheeks of said frame, adjustable gibs, and lock-nuts, substantially as described.

4. In combination with slideways which are

vertically and transversely adjustable, means, substantially as described, for adjusting and locking said slideways, for the purpose specified.

5 5. In the combination of the recessed slide-ways with laterally-adjustable screw-bolts and endwise-adjustable gibbs, substantially as described.

6. The combination of the support having 10 angular cheeks, the angular slideways supported thereon, with the angular gibbs C and the bolts E and F, for locking said slideways, substantially as described.

7. The combination of the support having angular cheeks, the slideways B, supported thereon and slotted substantially as described, with the gibbs C and the locking bolts and nuts, all substantially as described. 15

In testimony that I claim the foregoing as my own I affix my signature in presence of 20 two witnesses.

VIRGIL W. BLANCHARD.
